UNITED STATES PATENT OFFICE

2,154,330

WINDOW

Hugh Hanley and Emile Nielsen, Kankakee, Ill.

Application March 8, 1937, Serial No. 129,733

1 Claim. (CL. 189—64)

Our invention relates to locomotives and has among its objects and advantages the provision of an improved cab window.

In the accompanying drawing:

Fig. 1 is an elevational view of a locomotive cab door showing our invention applied thereto, which view is taken from a position exteriorly of the cab;

Fig. 2 is an elevational view of the window taken from a position interiorly of the cab;

Fig. 3 is a sectional view along the line 3—3 of Fig. 2;

Fig. 4 is a sectional view along the line 4—4 of Fig. 2;

Fig. 5 is a sectional view along the line 5—5 of Fig. 4; and

Fig. 6 is a fragmentary perspective view of our window.

In the embodiment selected to illustrate our invention, we make use of a locomotive cab 10 including a conventional door 12 which is located on the forward wall of the cab and may be opened and closed in any conventional manner. The door 12 includes a frame 14 and glass panes 16 and 18. These panes are fixedly carried by the frame. Our window is indicated generally at 20 in Fig. 1.

Specifically, our window comprises a frame 22 having its vertical reaches 24 fitting snugly within the frame 14 (see Fig. 4). Lugs 26 are formed integrally with the frame 22 and are arranged in overlapping relation with the inner faces of the frame 14 and secured thereto by bolts 28. In Fig. 4, we illustrate the panes 16 and 18 as having overlapping relation at 30 with the horizontal reaches 32 of the frame 22, the margins of which panes may be rendered weather-proof by putty 34.

Within the frame 22 we mount an inner frame 36 which includes vertical reaches 38 having angular faces 40 arranged in wedging relation with corresponding angular faces 42 on the vertical reaches 24 of the outer frame. The lower horizontal reach 32 of the frame 22 is provided with an angular face 44 having wedging relation with the corresponding angular face 46 on the lower horizontal reach 48 of the frame 36. Such wedging relation establishes a weather-proof joint between the contacting faces of the two frames.

In Fig. 4, we illustrate the upper horizontal reach 49 of the frame 36 as being provided with a wall 50 lying in abutting relation with a rib 52 depending from the upper horizontal reach 32 of the frame 22. The frame 36 carries two lugs 54 which loosely receive a shaft 56 having its

ends journaled in the vertical reaches 24 of the frame 22 (see Figs. 4 and 5). Thus, the frame 36 is hingedly connected with the frame 22 and may be pivoted outwardly to an open position about the shaft 56 as an axis. A quadrant 58 has one end connected with an extension 60 projecting from the frame 36. This end of the quadrant is bored for the reception of a screw 62 having threaded relation with the extension 60, which screw includes a shoulder 64 having abutting relation with the extension 60 so as to provide free pivotal action for the connected end of the quadrant. In Fig. 3, we illustrate the quadrant as extending through an opening 66 in one of the frame reaches 14 and through an aligned opening 68 in a lug 70 projecting laterally from one of the vertical reaches 24. The lug 70 terminates in an ear 72 which carries a set screw 74 for fixedly securing the quadrant at various adjusted positions. In Fig. 4, the lug 70 is illustrated as being provided with a fixed tooth 76 arranged to receive the notches 78 whereby the weight of the window in its adjusted position may be carried by the tooth 76 and the set screw 74 utilized for holding the tooth in operative relation with one of the recesses 78.

All the reaches 38, 48 and 49 of the frame 36 are provided with inwardly extending flanges 80 against which we place an outer glass pane 82. This pane is urged against the flanges 80 by a pressure frame 84 which is positioned inside the frame 36. In Fig. 4, we illustrate the lower reach of the pressure frame 84 as being positioned within a flange 86 carried by the reach 48. The flange is so positioned as to hold the frame 80 in firm relation with the pin 82. The upper reach of the frame 84 is held in place by means of a wing nut 88 having a flange 90 arranged in slight overlapping relation with the frame. The wing nut 88 has threaded relation with a stud 92 anchored in the reach 49.

The pressure frame 84 may be removed by merely unscrewing the wing nut 88 and pushing the upper part of the frame inwardly of the cab 10. After the upper part of the frame has been moved slightly, the lower part of the frame may be lifted out of holding relation with the flange 86. An inner glass pane 94 is mounted within the pressure frame 84. The latter is provided with flanges 96 against which the pane 94 is urged by means of bowed flat springs 98. The ends of the springs project through slots 100 in the upper and lower horizontal reaches 96 of the pressure frame 84, and the ends of the springs are arranged in abutting relation with the reaches 48.

and 49 so as to be supported in bowed relation and in pressure contact with the pane 94. We arrange the springs 98 to lie within the margins of the vertical flanges 96 in the pressure frame 84, thus being located out of sight obstructing relation with the pane 94.

Fig. 3 illustrates one of the vertical reaches of the pressure frame 84 as being provided with a slot 102 through which the pane 94 may be pushed 10 for assembly purposes.

The glass panes 82 and 94 are arranged in spaced relation and cooperate to provide an efficient storm window. The air space operates to prevent frosting of the glass so that clear vision 15 may be had. To cooperate with the air space in maintaining clear vision we mount an electrically heated element 104 between the glass panes 82 and 94. In Fig. 5, we illustrate the heating element as extending vertically along the two 20 vertical reaches of the pressure frame 84 and horizontally along its lower horizontal reach. One end of the heating element is connected with a screw 106 which is grounded to the locomotive, and the heating element passes through insulating 25 bushings 108 carried by supports 110 hooked over the cut away corners 112 of the pressure frame. The opposite end of the heating element is connected with a shaft 114 (see Fig. 4), which shaft is supported within an insulating bushing 116 mounted within an opening in the upper 30 flange 96 of the pressure frame 84. The outer end of the shaft 114 is provided with threads for the reception of conventional nuts and screws 118 between which the terminal 120 attached to a 35 conductor 122 is connected. The conductor leads to a source of current such as the headlight circuit for the locomotive. In Fig. 5, we illustrate the upper flange 96 of the pressure frame 84 as being offset at 124 for accommodating the 40 shaft 114.

To the upper horizontal reach of the frame 22 we mount a conventional wind shield wiper motor 126 which is provided with a conductor 128 which 45 may be connected with the electric circuit of the locomotive. Since the motor 126 may be of conventional design, no further description thereof is

required. We show the motor as being secured in position by means of screws 130 which have threaded relation with the frame 22. The motor 126 is connected with the oscillating shaft 132 which is rotatably mounted in an opening in the 5 frame 22. To the end of the shaft 132 we connect a conventional wind shield wiper 134 which is arranged to sweep back and forth upon the outer face of the glass pane 82.

A trough 136 is carried by the reach 48, which 10 trough is elevated intermediate of its ends, as indicated at 138 in Fig. 1 for deflecting water running therein to the sides of the door 12.

Our invention embodies a storm window which 15 may easily be connected with a locomotive cab door, which storm window operates to provide clear vision for the occupants of the cab under all conditions of service. In the closed position 20 of the storm window an effective weather-tight condition is attained, but the storm window may be adjusted to various open positions and secured in such positions of adjustment through the medium of the quadrant 58. The wiper 134 operates to sweep off any accumulation of snow or 25 heavy rain which might otherwise obstruct clear vision, while the spaced panes and the heating device operate to prevent frosting of the window. The electrical facilities may be connected with the electric circuit of the locomotive.

Without further elaboration, the foregoing will 30 so fully explain our invention that others may, by applying current knowledge, readily adapt the same for use under various conditions of service.

We claim:

In a device of the type described, a frame having flanges, a transparent pane positioned adjacent said flanges, a pressure frame positioned inside said first frame and bearing against said pane, a second pane mounted on said pressure frame, and resilient means cooperating with said 40 second frame and said second pane for holding the latter in position, said panes being spaced, to provide an air space.
